LINING MACHINE

Isidor Newman, New York, N. Y.

Application May 19, 1939, Serial No. 274,581

26 Claims. (Cl. 113—80)

This invention relates to lining machines. It is particularly directed to a machine for lining can caps or other articles with liquid sealing material.

An object of this invention is to provide a machine of the character described, which feeds the can caps or other articles to be lined, at regular intervals, rotates each cap about its axis and dispenses sealing material onto the cap only as the cap rotates, and has means to prevent discharge of sealing material if a cap is not fed into position to receive the sealing material.

A further object of this invention is to provide in a machine of the character described, means to synchronize the rotation of the caps with the discharge of the sealing material to the cap.

Still another object of this invention is to provide a strong, rugged and compact machine of the character described, which shall be relatively inexpensive to manufacture, smooth and positive in operation, and practical and efficient to a high degree in use.

Other objects of this invention will in part be obvious and in part hereinafter pointed out.

The invention accordingly consists in the features of construction, combinations of elements, and arrangement of parts which will be exemplified in the construction hereinafter described, and of which the scope of application will be indicated in the following claims.

In the accompanying drawings, in which are shown various possible illustrative embodiments of this invention:

Fig. 1 is a perspective view of a lining machine embodying the invention;

Fig. 2 is an elevational cross-sectional view of a portion of the improved machine shown in Fig. 1;

Fig. 3 is a cross-sectional view taken on line 3—3 of Fig. 2, and showing the liquid tank swung back into inoperative position, in dotted lines;

Fig. 4 is an enlarged, cross-sectional view taken on line 4—4 of Fig. 2, and showing the normally inoperative position of the nozzle carrying ring and another position of the ring operating member in dotted lines;

Fig. 5 is a cross-sectional view taken on line 5—5 of Fig. 4;

Fig. 6 is a cross-sectional view taken on line 6—6 of Fig. 5;

Fig. 7 is a cross-sectional view taken on line 7—7 of Fig. 4;

Fig. 8 is a view similar to Fig. 7, but showing the position of the parts where there is no cap on the spindle;

Fig. 9 is a view similar to Fig. 4, but showing a machine embodying the invention, illustrating a modified construction;

Fig. 10 is a cross-sectional view taken on line 10—10 of Fig. 9;

Fig. 11 is a cross-sectional view taken on line 11—11 of Fig. 9;

Fig. 12 is a perspective view of a scored and lined cap; and

Fig. 13 is a bottom perspective view of a cap cut in half.

Referring now in detail to the drawings, 10 designates a lining machine embodying the invention, for lining can caps 10a or the like articles with a liquid sealing material. Said machine comprises a base 11 on which is mounted a pair of parallel, upstanding, vertical frames 12 and 13.

The frame 12 has a top wall 14 formed with a central opening 15, and an offset opening 16. Fixed to the top wall 14, as by screws 17, and supported thereby, is a circular plate 18, having a central opening 19 registering with opening 15, and an offset opening 20 aligned with the offset opening 16.

Extending through the openings 15 and 19, is a vertical shaft 22 projecting above the plate 18. Fixed to the shaft 22 is a collar 23 extending within the opening 15 and contacting the underside of the circular plate 18. Fixed to the upper end of the shaft 22 is a collar 24. Received on said shaft, and below the collar 24, is a boss 25 fixed to said shaft by a set screw.

Fixed to the underside of the boss 25, and resting on the circular plate 18, is a circular plate 26 formed with a plurality of equiangularly spaced openings 27 of somewhat larger diameter than the openings 16 and 20, and adapted to successively register with said openings when said plate is rotated about the axis of shaft 22.

Means is provided to intermittently rotate the shaft 22, and hence the plate 26, through equal angles similar to the angles between the openings 27. To this end, there is fixed to the lower end of the shaft 22, a Geneva gear 30 having as many radial, equiangularly spaced slots as there are openings 27 in plate 26. Rotatably supported within the frame 12 is a vertical shaft 31 having a pawl 32 at its lower end cooperating with the Geneva gear 30. At the upper end of shaft 31 is a bevel gear 33.

Journalled within the frame 12, in any suitable manner, is a horizontal drive shaft 34 carrying a beveled gear 35, meshing with the beveled gear 33. The shaft 34 is driven by any suitable

power means to rotate the shaft 31, and hence to intermittently rotate the shaft 22 and plate 26, to successively bring the openings 27 into registry with openings 16, 20 at regular intervals.

Means is provided to feed the caps 10a, or any other articles to be lined, or to receive a liquid sealing material applied thereto in the manner hereinafter appearing, to openings in the plate 26. The feeding means may be similar to the mechanism shown in my co-pending application, Serial No. 248,741, filed December 31, 1938, for Work feeding device.

As shown in Fig. 1, the feeding means generally comprises an upwardly inclined chute 40 adapted to slidably receive the caps 10a, and a suitable support 41. Mounted on the chute 40 for transverse sliding movement thereon, is a plate 42 formed with an inclined by-pass groove 43 on the inner face thereof. Slidably mounted in one end of plate 42 is sheath member 42a having a pin and slot connection therewith, a spring being interposed between member 42a and one end of the plate. Pivoted to the frame 12, is a lever 44 connected to the frame by a coil tension spring 45. The upper end of the lever is connected in any suitable manner to the member 42a.

On the shaft 34 is a face cam 46 engaging a roller 47 at the lower end of the lever 44. As the shaft 34 rotates, the lever 44 is oscillated to reciprocate member 42a and hence the sliding plate 42, to permit the caps to come down the chute through by-pass groove 43 one at a time. The lever 44 is synchronized with the rotation of the plate 26, to permit one cap to drop down to the plate each time the plate is rotated to bring another opening 27 to the lower end of the chute.

Means is provided to lift and then rotate each cap as it is brought by the plate 26 to a position above the opening 20. To this end, there is fixed to the shaft 34 a gear 50.

Journalled on the frame 12 and 13 is a horizontal shaft 51, parallel to and aligned with the shaft 34. Carried by the shaft 51 is a gear 52 meshing with the gear 50. Fixed to the shaft 51 is a lift cam 53 disposed directly below the openings 16 and 20. Slidably mounted in the frame 12 is a member 54 carrying at its lower end a wheel 55 contacting the cam 53. Fixed to member 54 is a horizontal pin 56, passing through a vertical slot 57 in the frame 12. Attached to the pin 56 is a cross-bar 58, interconnected by a pair of coil tension springs 59 to pins 60, fixed to the frame and disposed below said cross-bar.

It will now be understood that the springs 59 tend to press the member 54 downwardly to keep the wheel 55 in contact with the lift cam 53. As the shaft 51 is rotated, member 54 is reciprocated vertically.

Mounted in the frame 12, in any suitable manner, for vertical sliding movement, as well as rotation, is a spindle 65, connected to member 54 by a rotary thrust bearing 66 and formed in its upper end with a socket opening or recess 65a, for the purpose hereinafter appearing. The spindle 65 reciprocates with member 54.

Means is provided for continuously rotating the spindle 65. To this end, there is journalled in frames 12 and 13, in any suitable manner, a horizontal shaft 66 carrying a bevel gear 67 meshing with a bevel gear 68 splined to the spindle 65. Shaft 66 is connected by sprocket chain gearing 70 to the shaft 51.

It will now be understood that when the drive shaft 34 is rotated, the caps will be intermittently fed to the openings 27 in plate 26. The plate 26 will intermittently carry the caps to a position above the openings 16 and 20, and the spindle 65 will be continuously rotated and also reciprocated upwardly through the opening 20. When the spindle is down, the plate 26 rotates. When the plate 26 is at rest, the spindle moves up and then down. When the spindle 65 moves upwardly, it lifts the cap 10a above the spindle and rotates the same, for the purpose hereinafter appearing.

As shown in Fig. 12, the cap 10a shown herein for the purpose of illustration only, comprises a bottom wall 72, an upwardly extending annular flange 73, and an outwardly and downwardly inclined flange 74. Between the flanges 73 and 74, is a channel or trough 75. The caps 10a are fed in inverted position, that is, with the bottom wall 72 at the top.

Means is provided for spraying a liquid sealing material into the channel 75 while the cap 10a is in lifted position and is being rotated by the spindle. To this end, there is attached to the top of the frame 13, a bracket 13a having a pair of aligned slots 76 receiving screws 77 screwed to the top wall of the frame. The slots 76 are in a vertical plane passing through the axis of shaft 22 and the axis of opening 20 or in a plane parallel thereto, whereby said bracket 13a may be adjusted toward or away from said opening.

The bracket 13a is provided with a boss 78 having a vertical bore 79 to receive the lower reduced end of a vertical post or rod 80. On the post 80 is a collar 81 adapted to be fixed thereto in vertically adjusted positions by a set screw 81a.

Rotatably mounted on the post 80, above the collar 81, is an annular ring clamp 82 having an offset sleeve 82a receiving said post and contacting collar 81, and adapted to be fixed to the post by a set screw 82b. Supported within and fixed to the clamp 82 is a vertical tank 83 containing the liquid sealing material. The top of the tank 45 may be closed by an air tight cover 84, whereby the tank may be provided with compressed air above the liquid sealing material.

By loosening the set screw 82b, the tank may be swung about the axis of the post 80. On the ring 81 is a vertical upwardly extending stop pin 81b which serves to limit rotation of the tank in one direction. The tank may also be swung out of the way, to a position where it is not used, as illustrated in dotted lines in Fig. 3 of the drawings.

At the lower end of the tank is a downwardly converging conical wall 85 formed at its apex with an internally, screw threaded, downwardly projecting nipple 86. Screwed to the lower end of the nipple 86 is a vertical pipe 87 formed with a central vertical through opening 88 communicating with the bottom of the tank. The lower end of the pipe 87 may be closed by a screw plug 90. The lower portion of the pipe 87 is formed with a downwardly and outwardly inclined, conical outer surface 91, for the purpose hereinafter appearing. Said lower portion of the pipe 87 is formed with a downwardly and outwardly inclined thin opening 91a communicating with the opening 88 of said pipe.

Rotatably mounted on the surface 91 of pipe 87, is an annular ring 93, having a tapering inner surface 94 corresponding to the tapering outer surface 91 of said pipe. The ring 93 is formed with an inclined screw threaded socket

96 and with a downwardly and outwardly inclined thin opening 91, which in one angular position of the ring registers with the opening 91a. Screwed within the socket 96 is a downwardly and outwardly inclined nozzle 97a formed with a thin through opening 98 communicating with the opening 97. The lower end of the opening 98 may be reduced in diameter, as shown in Fig. 5 of the drawings.

As seen in Fig. 5, the lower end of the nozzle 97a is just above the channel 75 in the cap 10a and points thereto when the cap is lifted by the spindle 65. When the spindle lifts the cap, and the ring is in the angular position shown in full lines in Figs. 4 and 5, openings 91a and 97 register and the material within the tank passes through the openings 91a, 97 and 98 to the channel 75 which receives the sealing material as the cap is rotated. When the ring 93 is rotated to disalign openings 91a and 97, the discharge of liquid is immediately stopped.

Means is provided to control the angular position of ring 93 for initiating the flow of sealing material to the channel 75 as soon as the cap is lifted, and to shut off the flow of sealing material when the cap is lowered, and to prevent any sealing material being discharged if there is no cap on the spindle.

To this end, there is clamped to the ring 93, a split clamp 93a having radial ears 93b clamped together by a screw 93c. The clamp 93a is formed with a radial projection 99 carrying an upwardly extending pin 99a, for the purpose hereinafter appearing. On the ring 93 is a thrust roller bearing 98c, pressed down against the ring 93 by a coil compression spring 99d, interposed between the thrust bearing and the lower end of the nipple 86.

On the frame 12 is a vertical upwardly extending pin 100. Rotatably mounted on the pin 40 100, is a horizontal arm 101 formed at its outer end with a vertical through opening in which is slidably mounted a vertical pin 102, co-axial with and disposed above the spindle 65. Fixed to the upper end of the pin 102 is a collar 103. When there is a cap on the upper end of the spindle, and the spindle is lifted, the cap will lift the pin 102. As the spindle 65 is lowered with a cap thereon, the pin 102 will likewise be lowered. However, if there is no cap on the upper end of the spindle, the lower end of the pin 102 will project downwardly into the opening 65a as the spindle is lifted, and the pin will not be lifted.

There is further fixed to the frame 12 a vertical pin 106 on which there is mounted a member 107 formed with a pair of spaced vertical walls 108 forming a slot 109 therebetween. Fixed to the walls 108 is a transverse pin 110 traversing the slot. Received within the slot 109, and pivoted to the pin 110 is a lever 111 having one end formed with an opening 112 disposed directly above the pin 102 and the axis of spindle 65.

Screwed within the opening 112 is an adjustable vertical pin 113 adapted to be contacted by the pin 102 when the latter is lifted by a cap on the spindle. If a cap is lifted, the pin 102 will rotate the lever 111 in a clockwise direction looking at Fig. 1 of the drawings, for the purpose hereinafter appearing.

Mounted on the frame 13 for rotation about its axis, is a vertical non-slidable shaft 115. Fixed to the upper end of the shaft 115 is a horizontal member 116 comprising a pair of parallel vertical walls 117 and 118, and a bottom wall 119. Between the walls 117 and 118 is a 70 75

slot 120. Within the slot 120 is a lever 121 pivoted at one end by a transverse pin 122 traversing the slot 120.

Interposed between the lever 121 and the bottom wall 119 is a coil compression spring 123 which normally tends to lift said lever. One end of the wall 118 is formed with a vertical through slot 125, for the purpose hereinafter appearing.

The front end of the bottom wall 119 is cut 10 away, as at 119a, and the lower edge of the front portion of the vertical wall 117 is likewise cut away, as at 117a.

The pin 99a on clamp 93a normally projects into the slot 125. Said pin 99a is aligned with the cut away portions 119a and 117a in the bottom wall 119 and the side wall 117. When there is no cap on the spindle or when the spindle is down and the pin 102 is not lifted, the spring 123 will raise the lever 121 to the position shown in Fig. 8 of the drawings, above the upper end of the pin 99a, and member 116 may be oscillated without turning ring 93.

Means is provided to oscillate the shaft 115 about its axis. To this end, there is fixed to the shaft 34, a face cam 134 contacting a roller 135 on an arm 136 offset from the shaft 115. The arm 136 is connected by a coil tension spring 137 to the frame 13, to retain the roller 135 in constant contact with the face of the cam 134.

It will now be understood that as the drive shaft 34 rotates, the shaft 115 will be oscillated in synchronism with the operation of the feeding mechanism and rotation of the plate 26. The ring 93 is normally in the dotted line position of Fig. 4, with the openings 91 and 97 disaligned so that no liquid is discharged. If there is no cap on the spindle, lever 121 is lifted by spring 123 above pin 99a and the shaft 115 oscillates member 116 without affecting the position of the ring 93.

The lever 111 has an offset arm 111a overlying the lever 121. If there is a cap on the spindle, as the spindle is raised the cap will lift the pin 102 to rotate the lever 111 for pressing the lever 121 downwardly, against spring 123, below the pin 99a. Said pin is then disposed between the forward end of the wall 118 and the forward end of the lever 121. As the shaft 115 oscillates member 116 to the full line position shown in Fig. 4, the ring 93 will be moved to the full line position shown in Fig. 4 to bring nozzle 97a directly above the channel 75 in the lifted cap, and register the openings 97 and 98 with the opening 91 to permit the sealing material to pass said channel of the rotating cap. As the arm 116 is oscillated in an opposite direction back to the dotted line position of Fig. 4, the ring 93 is rotated in a clockwise direction to disalign the nozzle in the opening 97 relative to the opening 91, to shut off the supply of sealing material.

It will be understood that the oscillation of the arm 116 is synchronized with the operation of the machine so that it begins to rotate in a clockwise direction, after the spindle is lifted, whereby the nozzle 97a can only be moved to dispensing position when a cap is lifted by the spindle.

Fixed to the top of frame 13 is a stop member 140 having vertical portions 141 carrying an adjustable stop screws 142, adapted to contact one of the radial projections 93b of the clamp 93a to limit angular rotation of said clamp in one direction.

It will be noted that by fixing the set screw 82b, the tank 83 may be rotated to the inoperative

dotted line position shown in Fig. 3. The arm 101 may also be swung out of the way about the vertical pin 108. Member 107 may also be swung about the pin 108 if desired.

It will be noted that the nozzle 91a moves in an arc and the sealing compound begins to spray upon the cap as soon as the openings 91 and 91a overlap. As the nozzle continues to move and the two openings progressively increase their overlap, the compound continues to spray upon the cap. Since the nozzle is spaced from the cap, a small arc of movement of the nozzle through which the sealing liquid is sprayed causes the spray to cover a larger angle at the point of application. Thus, the spraying may start even before the liquid touches the cap and the spray may continue as the nozzle passes back and forth, causing the spray to continue across the rim of the cap. This spraying action spreads the liquid and thereby distributes the same evenly to prevent coagulation in spots.

With the present construction, there is no dripping in one spot, as for example, in constructions in which the nozzle is stationary. The spraying may begin before the stream of liquid reaches the cap and may continue until the same is entirely off the cap.

By loosening the nuts 77, the bracket 78 may be adjusted to accommodate caps of various sizes. By loosening the screw 93c and turning the ring 83a relative to the rotary valve 93, the amount of liquid dispensed may be varied, so that the machine may be used with equal effectiveness for small caps requiring a smaller amount of sealing liquid, and with large caps requiring a greater amount of sealing liquid.

In Figs. 9, 10 and 11 there is disclosed a machine 142, embodying the invention, and illustrating a modified construction. In the machine 10 of Figs. 1 to 8, the nozzle carrying member 93 was rotatable to operative and inoperative positions. The machine 142 is similar to the machine 10, with the exception that in the former, the nozzle carrying member is stationary, an inner rotary valve or cock being provided, together with means for rotating the same to operative and inoperative positions, as will be explained in detail hereinafter.

To this end, there is screwed to the nipple 86 of the liquid tank 83, a member 143 having a nipple 144 at its upper end received within the threads of the nipple 86. Member 143 comprises an annular portion 145 carrying said nipple 144 and formed with an axial conical bore 146, and with a vertical passage 147 interconnecting the bore 146 with the nipple 144.

Extending downwardly from member 143 is a boss 148 formed with an internally screw threaded socket 149. Member 143 is furthermore formed with a vertical narrow passage 150 establishing communication between the socket 149 and the bore. Screwed to the socket 149 is a nozzle 151 pointing downwardly toward the channel 75 of a cap 10a on the spindle 65.

Rotatably mounted within member 143 is a valve or cock 154 having a frusto-conical portion 156 disposed within the bore 146. Extending from said portion 156, is a horizontal, axial portion 159, from which there extends a reduced portion 160 provided with a screw threaded stem 161.

Said portion 156 of member 154 is formed with an axial opening 156a closed at one end by a plug 156b, and also with a vertical upwardly extending passage 156c extending from the open-

ing 156a. Said portion 156 is furthermore formed with a downwardly extending vertical passage 156d communicating with the opening 156a.

As shown in Fig. 11 of the drawings, in one position of the valve, passage 156 registers with passage 147, and passage 156d communicates with passage 150. In such position, liquid from the tank will pass through the nozzle to be discharged to the channel 75 of the rotating cap when the spindle 65 is lifted. However, upon rotating the valve member 154, in the manner hereinafter appearing, to disalign the passages 156d and 150, the discharge of liquid through the nozzle is immediately cut off.

The valve 154 is normally in inoperative position. Means is provided, however, to rotate the valve 154 to operative position, only when there is a cap on the spindle and the spindle is lifted. To this end, there is fixed to valve 154, a horizontal arm 162 having an opening at one end receiving the reduced portion 160 and fixed thereto by a nut 163, screwed to the stem 161. On member 159 is a ball thrust bearing 166 pressed against portion 145 of member 143 by a coil compression spring 167 interposed between said thrust bearing and the arm 162.

Slidably mounted on the arm 162 for longitudinal movement, is a plate 170. Fixed to the plate 170 is a horizontal, outwardly extending pin 170a, for the purpose herein after appearing. The outer end of the arm 162 has a finger 171 parallel to the plate and disposed therebelow. When the plate 170 is moved outwardly in the manner hereinafter appearing, the outer end of the plate is parallel to the finger 171 forming a slot 172 therebetween.

On the frame 13 of the machine is a vertically, upwardly extending pin 175 carrying a bracket 176. Pivoted to the bracket 176 is a lever 177 having one end 178, disposed directly above the spindle 65. On the arm 178 of the lever is an adjustable screw 180, adapted to be engaged by the pin 102 on the arm 101.

The lever 177 has a second arm 182 formed with a slot 183 concentric with the axis of the valve 154 and receiving the pin 170a of the plate 170.

It will be noted that the pivot 177a for the lever 177 is disposed below the arm 162 and closer to the pin 170a, than the axis of the valve 154.

On the pivot 177a of the lever 177 is a torsion spring 186, normally tending to rotate the lever 177 in a counter-clockwise direction, looking at Fig. 10, to retain the screw 180 in contact with the pin 102.

On the drive shaft 34 is a face cam 190. Slidably mounted on the frame 13, in any suitable manner, is a vertical rod 191 disposed directly above the face cam. The lower end of the rod 191 is retained in contact with the face cam by a coil tension spring 192 interconnecting the rod with the frame. At the upper end of the rod is a pin 194 normally received in the slot 172. As the machine operates the rod 191 is reciprocated vertically.

If a cap is disposed above the spindle 65, and the spindle is lifted, lever 177 will be rotated in a clockwise direction, to a position shown in Fig. 10 of the drawings, for moving the plate 170 outwardly to the position shown in full lines in Fig. 10.

Upon lifting the rod 191, the valve 154 will be moved to position for registering the opening 156d with the opening 150, and the opening 156c with the passage 147 to permit discharge of liquid

to the cap. When the rod 191 is lowered, the valve becomes disaligned to cut off discharge of liquid. Thereafter, the spindle 65 is lowered.

Should there be no cap on the spindle, the lifting of the spindle 65 will not raise the pin 102, and the lever 117 will not be rotated in a clockwise direction, and the plate 170 will not be slidably moved outwardly, and then the rod 191 may reciprocate without rotating the valve. It will therefore be seen that unless there is a cap on the spindle no liquid will be discharged from the tank.

It will now be understood that the tank may be raised or lowered by adjusting the position of the collar 81 on the post 80 to accommodate caps or other articles of various sizes lifted by the spindle 65. Furthermore, the bracket 13a may be adjusted to bring the nozzle 97a in correct position depending upon the diameter of the cap or other article lifted by the spindle.

It will be observed that the ring 93a may be loosened by loosening the screw 93c and the ring may then be rotated relative to the rotary member 93, through a small angle, and then again tightened thereon. Such adjustment will vary the registration of the openings 91a and 97 from full registration to partial registration. Thus, the amount of liquid discharged each time the valve is rotated to discharging position may be varied so that the machine can be used for smaller caps as well as large caps. Likewise, as shown in Fig. 11, by loosening the nut 163, the arm 162 may be varied angularly with respect to the rotary valve 154, so that in discharging position, the registration between the openings 156 and 150 can be varied from full registration to partial registration, likewise varying the amount of liquid discharged each time the valve is in discharging position.

It will thus be seen that there is provided a device in which the several objects of this invention are achieved, and which is well adapted to meet the conditions of practical use.

As various possible embodiments might be made of the above invention, and as various changes might be made in the embodiments above set forth, it is to be understood that all matter herein set forth or shown in the accompanying drawings is to be interpreted as illustrative and not in a limiting sense.

Having thus described my invention, I claim as new and desire to secure by Letters Patent:

1. A lining machine of the character described, comprising a vertical spindle adapted to support an article to be lined, placed on the upper end of said spindle, means for reciprocating said spindle longitudinally of its axis to lift and lower said article, a receptacle adapted to contain lining liquid, valved means to control discharge of liquid from said receptacle onto said article, including a rotary member adapted in one angular position to permit discharge of liquid from said receptacle onto said article, and in another angular position thereof to cut off discharge of lining liquid from said receptacle to said article, means for oscillating said rotary member, and means actuated by contact with said article on the upper end of said spindle to cause said oscillating means to oscillate said rotary member, and a nozzle on said rotary member adapted to point toward said article when said rotary member is in discharging position and point away from said article when said rotary member is in non-discharging position.

2. A machine of the character described com-

prising a vertical spindle adapted to support an article placed at the upper end thereof, means for reciprocating said spindle longitudinally of its axis for lifting and lowering said article, said spindle having a recessed opening at the upper end thereof, a member adapted to be moved by an article on the spindle when the spindle is lifted, a receptacle adapted to contain liquid to be applied to said article, valved means to discharge said liquid onto said article, including a rotary member adapted in one angular position thereof to prevent discharge of liquid therefrom onto said article, and in another angular position thereof to discharge liquid therefrom onto said article, means for oscillating said rotary member from the non-discharging position to discharging position, and then back to non-discharging position, while the spindle is in lifted position, said means being controlled by the member lifted by the article on the spindle, said first member being adapted to project into the recessed opening at the upper end of the spindle, without being lifted, when the spindle is lifted, with no article thereon, and said oscillating means being inoperative to oscillate said rotary member, unless said first member is lifted by a cap on the spindle, and a nozzle on the rotary member adapted to point toward said article in the discharging position of said rotary member and away from said article in the non-discharging position of said rotary member.

3. A machine for applying liquid to articles comprising a vertical spindle adapted to support an article placed on the upper end thereof, means for reciprocating said spindle longitudinally of its axis to lift and lower said article, a receptacle adapted to contain liquid, valved means to control discharge of liquid from said receptacle onto said article, including a rotary member carrying a radial nozzle and adapted in one position to permit discharge of liquid from said receptacle onto said article, and in another position thereof, to cut off discharge of liquid from said receptacle to said article, means synchronized with the movement of the spindle, for oscillating said member from discharging to non-discharging positions, said spindle having a recess at its upper end, means for supporting a pin for sliding movement directly above said spindle, said pin being adapted to be lifted by an article on said spindle when the spindle is lifted, and said pin being adapted to project into said recess, should the spindle be lifted without an article thereon, and means controlled by said pin for releasing said oscillating means from said member.

4. A machine for lining can caps comprising a vertical spindle adapted to support a can cap at its upper end, means for reciprocating said spindle longitudinally of its axis, to lift and lower said cap, a receptacle adapted to contain sealing liquid, a rotary valve to control discharge of liquid from said receptacle onto said article, a nozzle on said valve, said nozzle being adapted to point towards said cap in one angular position of the valve, and said valve being open in such position, said valve being normally closed and in another angular position of said valve with said nozzle projecting away from said cap, a pin slidably mounted above said spindle and adapted to be lifted by the cap when the spindle is lifted with a cap thereon, a lever pivoted to the machine immediately the ends thereof, and having one arm disposed above said pin, and said pin being adapted to rotate said lever when said pin is lifted by a cap on the spindle, a vertical shaft

mounted for rotation about its axis on said machine, means synchronized with the movement of said spindle for oscillating said shaft, while the spindle is in lifted condition, an arm at the upper end of said shaft, and means controlled by rotation of said lever when said pin is lifted, to connect said arm to said rotary valve to oscillate said valve, and said arm being normally disconnected from said valve, whereby said valve remains closed unless a cap on the spindle lifts said pin.

5. In a machine of the character described, a vertical spindle, means for reciprocating the same longitudinally of its axis, a tank, a rotary valve controlling the discharge of liquid from said tank, means actuated by contact with an article on said spindle to rotate the valve to open position, and a nozzle on said valve rotatable therewith adapted to point towards an article on the upper end of said spindle when the valve is open, and to point away from said article when the valve is rotated to closing position.

6. In a machine of the character described, a vertical spindle adapted to carry an article thereon, means for reciprocating the same longitudinally of its axis to raise and lower said article, a tank, a rotary valve controlling the discharge of liquid from said tank, a nozzle on said valve normally pointing away from the article on said spindle when the valve is closed, and means actuated by contact with an article on said spindle to rotate the valve to open position, and point said nozzle towards an article on the upper end of said spindle each time said spindle is in raised position as the spindle is reciprocated, and rotate said valve to normally closed position with the nozzle pointing away from said article each time the spindle is lowered during its reciprocation.

7. A machine of the character described, comprising a vertical spindle adapted to support an article placed on the upper end of the spindle, means for reciprocating said spindle longitudinally of its axis for lifting and lowering said article, a vertical post, a receptacle for liquid offset from the axis of the post and mounted on said post for rotation about the axis of said post, and for vertical movement, and means actuated by contact with the article on the spindle and synchronized with the movements of said spindle for dispensing predetermined amounts of liquid from said receptacle, onto said article each time the spindle is lifted with an article thereon, said last means including discharge means on said receptacle through which the liquid in the receptacle passes onto said articles.

8. A machine of the character described, comprising a vertical spindle adapted to support an article placed on the upper end of the spindle, means for reciprocating said spindle longitudinally of its axis for lifting and lowering said article, a vertical post, a receptacle for liquid offset from the axis of the post and mounted on said post for rotation about the axis of said post, means controlled by the article on the spindle and synchronized with the movements of said spindle for dispensing predetermined amounts of liquid from said receptacle, onto said article each time the spindle is lifted with an article thereon, said last means including discharge means on said receptacle through which the liquid in the receptacle passes onto said articles, a bracket supporting said post, and means for adjusting the position of said bracket toward or away from

said spindle and for fixing said bracket in adjusted position.

9. A machine of the character described, comprising a vertical spindle adapted to support an article placed on the upper end of the spindle, means for reciprocating said spindle longitudinally of its axis for lifting and lowering said article, a vertical post, a receptacle for liquid offset from the axis of the post and mounted on said post for rotation about the axis of said post, means controlled by the article on the spindle and synchronized with the movements of said spindle for dispensing predetermined amounts of liquid from said receptacle, onto said article each time the spindle is lifted with an article thereon, said last means including discharge means on said receptacle through which the liquid in the receptacle passes onto said articles, a bracket supporting said post, means for adjusting the position of said bracket toward or away from said spindle and for fixing said bracket in adjusted position, and means for adjusting the vertical position of said receptacle and for fixing said receptacle in vertically adjusted position.

10. A machine of the character described, comprising a vertical spindle adapted to support an article placed on the upper end of the spindle, means for reciprocating said spindle longitudinally of its axis for lifting and lowering said article, a vertical post, a receptacle for liquid offset from the axis of the post and mounted on said post for rotation about the axis of said post, means controlled by the article on the spindle and synchronized with the movements of said spindle for dispensing predetermined amounts of liquid from said receptacle, onto said article each time the spindle is lifted with an article thereon, said last means including discharge means on said receptacle through which the liquid in the receptacle passes onto said articles, a bracket supporting said post, means for adjusting the position of said bracket toward or away from said spindle and for fixing said bracket in adjusted position, and means for adjusting the vertical position of said receptacle and for fixing said receptacle in vertically adjusted position.

11. In a machine of the character described, a member having a longitudinal passage and formed at the lower end thereof with an outer, upwardly and inwardly tapering conical surface, a ring mounted on said member for oscillation and having an inner upwardly and inwardly tapering conical surface contacting the first mentioned conical surface, said member being formed with a transverse passage communicating with said longitudinal passage and extending to said outer conical surface thereof, and a nozzle on said ring, said ring being formed with a passage communicating with the nozzle, and adapted, in one angular position of the ring relative to said member, to register with the transverse passage of said member, and means for pressing said ring downwardly.

12. A lining machine comprising a vertical spindle adapted to support an article to be sprayed, means for reciprocating said spindle to lift and lower said article, a receptacle adapted to contain lining liquid, a rotary valve to control discharge of liquid from said receptacle onto said article, a nozzle on said valve rotatable therewith, said nozzle being adapted to point toward said article in one angular position of said valve, and said valve being open in such position, said valve being closed in another angular position thereof, with the nozzle pointing away from said article, a member above said spindle adapted to be moved by an article on the spindle when said spindle is lifted with said article thereon, a lever pivoted mediate the ends thereof and having

one arm disposed above said member, and said member being adapted to rotate said lever when said member is lifted by an article on the spindle, a member mounted for rotation about an axis parallel to said spindle, means synchronized with the movement of the spindle for oscillating said second member while the spindle is in lifted condition, an arm on said second member, and means controlled by rotation of said lever when said first member is lifted to connect said arm with said rotary valve, to oscillate said valve, said arm being normally disconnected from said valve, whereby said valve remains closed unless an article on the spindle raises said first member.

13. In a machine of the character described, a vertical spindle, means for rotating said spindle vertically about its axis, a receptacle, a rotary valve controlling the discharge of liquid from said receptacle, means controlled by an article on said spindle in raised position to rotate the valve to open position, and a nozzle on said valve rotatable therewith and adapted to point toward an article on the upper end of the spindle when the valve is open, and to point away from said article when the valve is rotated to closing position.

14. In combination, a member having an opening, a second member mounted on said first member for oscillation thereon, and having an opening adapted to register with the first opening in one angular position of said oscillatory member, a nozzle on said oscillatory member communicating with the opening in said oscillatory member, said nozzle being adapted to discharge material at a point spaced from the axis of said oscillatory member, and a member clamped to said oscillatory member and adapted to be fixed thereto in various relative angular positions, and means to support an article in position to receive discharge from said nozzle in the above mentioned angular position of said oscillatory member, and said nozzle pointing away from said article, in another angular position of said oscillatory member, and means controlled by said supporting means to oscillate said oscillatory member.

15. In a machine of the character described, a tubular member, said tubular member being formed with a transverse through opening, a ring mounted on said tubular member for oscillation thereon and having a transverse through opening adapted to register with the first opening in one angular position of said ring, a nozzle on said ring communicating with the opening in said ring, said nozzle being adapted to discharge material at a point spaced from the axis of said oscillatory member, and means to support an article in position to receive discharge from said nozzle in the above mentioned angular position of said ring, and said nozzle pointing away from said article in another angular position of said ring, and means controlled by said supporting means to oscillate said ring.

16. In a machine of the character described, a tubular member, said tubular member being formed with a transverse through opening, a ring mounted on said tubular member for oscillation about the axis of said member, and having a transverse through opening adapted to register with the first opening in one angular position of said ring, a nozzle on said ring communicating with the opening in said ring, a clamp on said ring and adapted to be fixed thereto in various relative angular positions, a pin on said clamp,

an oscillating arm, and a member pivoted to said arm and adapted to engage said pin.

17. A machine of the character described comprising a vertical member adapted to support an article, means for reciprocating said member vertically, a receptacle for liquid, a rotary valve controlling discharge of liquid from said receptacle onto said article, means for opening and closing the valve to dispense a predetermined amount of liquid from said receptacle onto said article each time said member is reciprocated, said means being controlled by said vertical member, and means for adjusting the degree to which the valve is opened each time said member is reciprocated, to vary the amount of liquid dispensed when the valve is opened.

18. A machine of the character described comprising a vertical spindle adapted to support an article placed on the upper end of said spindle, means for reciprocating said spindle longitudinally of its axis for lifting and lowering said article, a receptacle for liquid, a rotary valve controlling discharge of liquid from said receptacle onto said article, means actuated by contact with the article on said spindle and synchronized with the movements of said spindle for opening and closing the valve to dispense a predetermined amount of liquid from said receptacle onto said article each time said spindle is reciprocated, and means for adjusting the degree to which the valve is opened each time said spindle is reciprocated to vary the amount of liquid dispensed when the valve is opened.

19. A machine of the character described comprising a spindle, means for reciprocating said spindle for lifting and lowering an article deposited over said spindle, a receptacle for liquid, and means including a rotary valve carrying a nozzle for dispensing liquid from said receptacle onto said article automatically upon lifting the spindle and for shutting off the discharge of liquid onto said article when said spindle is lowered, said means being adapted to rotate said rotary valve only when the spindle is lifted with an article thereon.

20. A lining machine comprising a spindle on the upper end of which the article to be lined may be deposited, means for vertically reciprocating said spindle, a receptacle adapted to contain lining liquid, a movable valve adapted to control discharge of liquid from said receptacle, a nozzle on said valve and movable therewith, said valve being normally closed, and in a position where the nozzle points away from said spindle, means for moving said valve to a position where the nozzle points toward the article on the spindle when the spindle is lifted, and to a position where the nozzle points away from said spindle when the spindle is lowered, and means for opening the valve when the nozzle points toward said article to discharge liquid from said receptacle onto said article.

21. A lining machine comprising a spindle on the upper end of which the article to be lined may be deposited, means for vertically reciprocating said spindle, a receptacle adapted to contain lining liquid, a rotary valve adapted to control discharge of liquid from said receptacle, said valve being normally closed, means for rotating said valve to open position when the spindle is lifted, and to closed position when the spindle is lowered, and means to adjustably vary the limit of rotation of said valve to open position, and the degree of opening of said valve each time it is

opened, being dependent upon the limit of rotation of said valve to open position.

22. A lining machine comprising a spindle on the upper end of which the article to be lined may be deposited, means for vertically reciprocating said spindle, a receptacle adapted to contain lining liquid, a rotary valve adapted to control discharge of liquid from said receptacle, said valve being normally closed, means for rotating said valve to open position when the spindle is lifted, and to closed position when the spindle is lowered, and means to adjustably vary the limit of rotation of said valve to open position, and the degree of opening of said valve each time it is opened, being dependent upon the limit of rotation of said valve to open position, said spindle having a recess in its upper end, a member disposed above said spindle controlling the operation of said rotating means and adapted to be lifted by contact with an article on said spindle when said spindle is lifted with an article thereon, and said member being adapted to project into said recess when said spindle is lifted without an article thereon, whereby if said spindle is lifted without an article thereon, said member will not be lifted, and the rotating means will not rotate said valve from normal position.

23. A lining machine comprising a spindle on the upper end of which the article to be lined may be deposited, means for vertically reciprocating said spindle, a receptacle adapted to contain lining liquid, a movable valve adapted to control discharge of liquid from said receptacle, a nozzle on said valve and movable therewith, said valve being normally closed, and in a position where the nozzle points away from said spindle, means for moving said valve to a position where the nozzle points toward the article on the spindle when the spindle is lifted, and to a position where the nozzle points away from said spindle when the spindle is lowered, and means for opening the valve when the nozzle points toward said article to discharge liquid from said receptacle onto said article, means to adjustably vary the limit of movement of said valve when said valve is moved to open position by said moving means, and the amount of opening of said valve each time it is opened, being dependent upon the limit of movement of said valve to open position.

24. A lining machine comprising a spindle on the upper end of which the article to be lined may be deposited, means for vertically reciprocating said spindle, a receptacle adapted to contain lining liquid, a movable valve adapted to control discharge of liquid from said receptacle, a nozzle on said valve and movable therewith, said valve being normally closed, and in a position where the nozzle points away from said spindle, means for moving said valve to a position where the nozzle points toward the article on the spindle when the spindle is lifted, and to a position where the nozzle points away from said spindle when the spindle is lowered, and means for opening the valve when the nozzle points toward said article to discharge liquid from said receptacle onto said article, said spindle having a recess in its upper end, a vertical rod above said spindle controlling the operation

of said moving means and adapted to be lifted by contact of an article on the spindle when the spindle is lifted with an article thereon, the lower end of said rod being adapted to project into said recess when the spindle is lifted without an article thereon, whereby if said spindle is lifted without an article thereon, said rod will not be lifted, and said valve will not be moved from normal positions by said moving means.

25. A lining machine comprising a spindle on the upper end of which the article to be lined may be deposited, means for vertically reciprocating said spindle, a receptacle adapted to contain lining liquid, a movable valve adapted to control discharge of liquid from said receptacle, a nozzle on said valve and movable therewith, said valve being normally closed, and in a position where the nozzle points away from said spindle, means for moving said valve to a position where the nozzle points toward the article on the spindle when the spindle is lifted, and to a position where the nozzle points away from said spindle when the spindle is lowered, and means for opening the valve when the nozzle points toward said article to discharge liquid from said receptacle onto said article, said spindle having a recess in its upper end, a vertical rod above said spindle controlling the operation of said moving means and adapted to be lifted by contact of an article on the spindle when the spindle is lifted with an article thereon, the lower end of said rod being adapted to project into said recess when the spindle is lifted without an article thereon, whereby if said spindle is lifted without an article thereon, said rod will not be lifted, and said valve will not be moved from normal position by said moving means, means to adjustably vary the limit of movement of said valve when moved to open position by said moving means, and the amount of opening of said valve each time it is opened, being dependent upon the limit of movement of said valve to open position.

26. In a machine of the character described, a vertical spindle, means for reciprocating said spindle for lifting and lowering an article deposited on the spindle, a receptacle for liquid, means for dispensing liquid from said receptacle onto said article, automatically upon lifting said spindle with an article thereon, and for shutting off the discharge of liquid from said receptacle to said article when said spindle is lowered, and to prevent discharge of liquid from said receptacle should the spindle be lifted without an article thereon, said means comprising an oscillatory valve adapted to open and close during each oscillation thereof for controlling the discharge of liquid from said receptacle, the degree of opening of said valve being dependent upon the limit of rotation of said valve in one direction during each oscillation thereof, a member adjustably attached to said oscillatory valve, means synchronized with the movement of said spindle to oscillate said member for oscillating said valve therewith, and means controlled by contact with an article on said spindle to connect the oscillating means to said member.
